SAW HOLDER

David T. Anderson, Montreal, Quebec, Canada
Application October 5, 1935, Serial No. 43,767

4 Claims. (Cl. 76—78)

The present invention relates to improvements in saw holding devices.

An important object of the invention is the provision of a device which will hold a saw blade 5 firmly and in convenient tooth filing position.

Another object of the invention is the provision of a saw holding device designed to enable resilient engagement of a saw.

A further object of the invention is the provision of a saw holding device constructed so as to enable quick and easy insertion or removal of a saw blade.

Still another object of the invention is the provision of a saw holding device which may be conveniently transported and easily mounted in working position.

A still further object of the invention is the provision of a saw holding device of the aforesaid character which may be suitably mounted in a 20 kerf in a stump, log or the like.

Still another object of the invention is the provision of a saw holding device capable of supporting a saw in a vertical or in various inclined positions.

A still further object of the invention is the provision of a saw holding device of the above character which is simple, durable and compact in construction.

Other objects and advantages of the invention 30 will become apparent as the description progresses.

In the accompanying drawing forming a part of this specification and in which like reference characters are employed to designate corresponding parts throughout the same:—

Figure 1 is a perspective view of the device,

Figure 2 is a side elevational view, partly broken away to show the interior construction,

Figure 3 is a transverse section on line 3—3 40 of Figure 2,

Figure 4 is a similar view showing parts of the device in separated arrangement,

Figure 5 is a side elevational view showing one manner in which the device may be mounted,

Figure 6 is an enlarged section taken on the line 6—6 of Figure 5, and

Figure 7 is a transverse section showing another manner of mounting the device.

Referring to the drawing, wherein for the purpose of illustration is shown a preferred embodiment of the invention, 10 designates the body of the holder preferably formed of a length of sheet or cast metal having the form of an inverted V in cross section so as to provide side sections converging to a centrally disposed top ridge. In

each of the side sections of the body 10 is provided a bottom row of longitudinally spaced holes 11 and an upper row of longitudinally spaced holes 12.

The upper row of holes 12 in the body are 5 adapted to slidably receive therein assembly screws 14 disposed to extend through the side sections and to engage threaded holes 15 disposed at properly spaced positions in elongated metallic fastening bars 16 disposed against the 10 inner surface of each side section. The screws 14 are disposed to support longitudinal holding strips 17 on the upper parts of each outer side face of the body, each of the holding strips being provided with holes 18 to receive the screws. 15 These holding strips 17 are preferably formed of resilient material, as for instance, spring steel.

Between the holding strips 17 and the side sections of the body are interposed elongated relatively narrow spacing strips 20 provided at spaced 20 intervals with transverse slots 21 to permit the passage of the screws 14. When these elements are assembled, as shown at Figures 1 and 3, the upper edges of the longitudinally disposed holding strips 17 project above the ridge of the body 25 and assume transversely spaced positions.

During use of the device to hold the saw blade in position for filing the saw teeth, the saw is slidably inserted in the grooves 22 formed on each top side of the body between each side 30 section and the upper marginal portion of the holding strips 17. When a relatively narrow blade, such as the blade of a web or band saw, is to be filed the spacing strip 20 of the groove forming assembly in which the blade is to be 35 fitted is arranged in an elevated position, as shown at Figures 2 and 3, so that the body of the blade will be snugly fitted in the groove while the teeth will project fully beyond the same, as shown in dotted lines at Figure 1. If a saw having a somewhat wider blade is to be fitted in the device, the spacing strip may be adjusted in correspondence with the increased width of blade by loosening the screws 14 and sliding the spacer transversely downward on the body, increasing the depth of the blade engaging groove 45 to assure firm engagement of the blade in the device.

As will be readily noted from the foregoing the saw blade may be quickly and conveniently inserted into the holding groove and removed without operation of screws or other movable parts.

As illustrated at Figure 3, the respective holder strips 17 may be disposed so that the blade in the groove at one side of the body will bear 55

against the upper edge of one holder strip while resiliently engaged by the other, so that the blade is firmly held in position for tooth filing. Furthermore, the holder may be employed in various ways, as for instance resting the body on the lower edges with both sides sloping, as at Figure 3, or securing one side section of the body in a vertical or approximately vertical position. As will be noted at Figures 5 and 6, the device may be quickly and easily set up on various numbering locations by cutting a kerf in an upstanding stump or log and fitting the lower margin of one side section of the body therein so that one side will assume an approximately vertical position while the opposed side section will be arranged at an inclination. The device may also be readily secured to a work bench or table, as shown at Figure 7, by disposing the lower margin of one side section of the body against the side edge of the table and fastening the same by screws or the like. It will thus be apparent that the device may be mounted to support a saw blade in vertical as well as in variously inclined positions to permit filing of the teeth at a desired bevel. Furthermore, the construction of the device will eliminate objectionable vibration during the tooth filing operation.

It is to be understood that the form of my invention herein shown and described is to be taken as a preferred example of the same, and that various changes as to the shape, size and arrangement of parts may be resorted to without departing from the spirit of the invention or the scope of the subjoined claims.

Having thus described my invention, I claim:—

1. A saw holding device comprising an elongated body having transversely inclined sides converging to a top ridge, and resilient groove forming strips disposed on each of the said sides, the said respective strips being arranged so that a blade disposed in one groove will be resiliently pressed against the top edge of the complementary groove strip on the other side.

2. A saw holding device comprising an elongated V-shaped body, a holding strip mounted longitudinally on the outer face at each side of the body adjacent the top, the said strips being disposed so that when a saw blade is clamped by one holding strip it is supported against the top edge of the other strip, a spacing strip interposed between each of the said first mentioned strips and the body whereby to form longitudinal grooves at the top of the body disposed to engage saw blades, and means for removably connecting the said strips with the body.

3. A saw holding device comprising an elongated body of V-shaped cross section, the said body having sloping sides converging toward a ridge at the top, a resilient holding strip attached to the outer face of each sloping side of the body, the said strips being disposed so that when a saw blade is clamped by one holding strip it is supported against the top edge of the other strip, and a spacing strip interposed between the holding strip and the body providing a groove between each holding strip and the body adapted to detachably engage a saw blade to firmly hold the same with the teeth projecting upwardly of the body.

4. A saw holding device comprising an elongated body of V-shaped cross section, the said body having sloping sides converging toward a ridge at the top, a resilient holding strip attached to the outer face of each sloping side of the body, the said strips being disposed so that when a saw blade is clamped by one holding strip it is supported against the top edge of the other strip, a spacing strip interposed between the holding strip and the body providing a groove between each holding strip and the body adapted to detachably engage a saw blade to firmly hold the same with the teeth projecting upwardly of the body, and means whereby the spacing strips may be moved transversely on the body to vary the depth of the saw blade engaging grooves.

DAVID T. ANDERSON.
